OIL COOLER FOR ENGINES

Walter R. Ramsaur, Los Angeles, Calif., assignor
to The Garrett Corporation, Airesearch Manufacturing Company Division, Los Angeles, Calif., a corporation of California

Application April 30, 1940, Serial No. 332,612

8 Claims. (Cl. 257—2)

My invention relates to improvement in oil coolers of the type used to cool the oil employed for crank case lubrication in internal combustion engines.

Coolers of this type are now being extensively employed with powerful internal combustion engines, such as used in transport and military aircraft, to minimize the disadvantages resulting from the decrease in viscosity and the deterioration of lubricating oil at high temperatures. As the temperature of the oil is increased, the viscosity and lubricating value of the oil rapidly decreases. One authority advises that the rise in temperature of lubricating oil from 100° F. to 210° F. results in a decrease in the viscosity of the oil to approximately one-twelfth of its viscosity at 100° F. Lubricating oils are now considered internal coolants for engines. Excessively high temperatures of the oil results in rapid deterioration of the oil at the elevated temperatures. Oil coolers are now in use with internal combustion engines, wherein the heated oil is brought into heat exchanging relation to a cooling medium by passing the oil into spaces or passages which lie in close relation to other spaces wherein the cooling medium, for example, air or water, is circulated. To maintain high efficiency in these oil coolers, the oil passages are made relatively narrow so that a large portion of the oil will be in contact with the walls of the passages, the result being that when the oil is cold and consequently in viscous state, it either will not flow at all or will flow very slowly through the oil spaces or passages of the oil cooler. To overcome the disadvantages of the foregoing condition it has become a practice to provide warm-up means in connection with the oil cooler.

It is an object of the present invention to provide an oil cooler having incorporated therein a simple and effective warm-up means, and at the same time to provide an oil cooler of more durable and rigid construction than previously employed in oil coolers of compact form and high efficiency.

It is a further object of the invention to provide an oil cooler having an automatic control to by-pass oil from the engine so that such oil will pass around the oil cooling spaces or passages of the cooler, when the oil is at low temperature and in a condition of relatively high viscosity, and wherein heat from this by-passed oil will be effectively employed to warm up the oil cooling spaces or passages of the cooler.

In my present oil cooler baffles are employed within a shell to divide the interior of the shell into spaces or passages through which the oil

to be cooled is directed, and it is an object of the invention to make one or more of these baffles hollow and to provide means for by-passing oil through these hollow baffles, whereby the bypassed oil will be brought into effective heat exchanging relation to oil in the normal oil spaces or passages of the oil cooler.

It is an object of the invention to provide an oil cooler having a shell wherein baffles or partition walls are employed to provide spaces to receive the oil which is to be cooled, and to employ within the shell in suitably spaced relation hollow partition walls which will form passages for a warm-up fluid, thereby making it possible to effectively distribute the passages for accommodation of the warm-up fluid within the shell of the cooler with the result that the warm-up is efficiently accomplished.

It is an object of the invention to provide an oil cooler of the character set forth in the preceding paragraph having control means whereby the oil is directed through a by-pass when it is cold and is proportionately directed through oil cooling spaces of the oil cooler as the temperature gradually increases, until a condition is reached wherein the oil has been brought to maximum operating temperature, and at which time substantially all of the oil from the crank case of the engine may pass through the oil cooling spaces of the cooler.

A further object of the invention is to provide in an oil cooler a simple construction wherein partition walls are installed within the shell of the cooler in a manner to reinforce the cooler structure and provide by-pass channels through the interior space of the shell in heat exchanging relation to oil in the oil cooling spaces of the shell, and wherein an effective distribution of the oil to be cooled is obtained, thereby achieving high efficiency in the operation of the cooler.

It is an object of the invention to increase the effectiveness of the thaw-out means by use of a structure wherein the thaw-out chambers are relatively close together, wherein back pressure is minimized by keeping the length of the thaw-out chambers within reasonable limits, and wherein the inlets and outlets of the cooling and thaw-out chambers are kept close together.

Further objects and advantages of the invention will be brought out in the following part of the specification.

Referring to the drawings which are for illustrative purposes only:

Fig. 1 is a plan view of a preferred embodiment of my invention.

Fig. 2 is a side elevation corresponding to Fig.

1, a portion of this view being broken away to show underlying structure.

Fig. 3 is an end elevation of the cooler taken from the position of the arrow 3 of Fig. 2.

Fig. 4 is a cross-section on a plane represented by the line 4—4 of Fig. 2.

Fig. 5 is a cross-section taken on a plane indicated by the line 5—5 of Fig. 2.

Fig. 6 is a fragmentary section taken as indicated by the line 6—6 of Fig. 2.

Fig. 7 is an enlarged longitudinal section taken on a plane represented by the line 7—7 of Fig. 4, intermediate portions of this view being broken away to condense the view.

Fig. 8 is a view similar to Fig. 7, but taken as indicated by the line 8—8 of Fig. 4.

Fig. 9 is a fragmentary sectional view taken as indicated by the line 9—9 of Figs. 4 and 7.

Fig. 10 is a bottom perspective view of the oil outlet port fitting employed in the oil cooler structure.

Fig. 11 is an enlarged fragmentary section taken as indicated by the line 11—11 of Fig. 2.

Fig. 12 is a diagrammatic view illustrating the unique positioning of the baffles and hollow 25 baffles and the direction of flow of liquid through the oil cooler.

The oil cooler comprises a shell 10 of tubular form, and preferably consists of a cylinder made by bending a sheet of copper to form a tube, the meeting or overlapping ends of the sheet being joined as indicated at 11 in Figs. 4 and 5. For purpose of clarity, I have in Figs. 3 to 6, inclusive, indicated edge elevations of thin sheets by double lines and have indicated sections of such sheets in heavy black lines, thereby making it possible to clearly distinguish openings through sheets from the adjacent portions of the sheets. For example, it will be noted that the edge of the shell 10 in Fig. 3 is in double lines, whereas in Fig. 4 the section of the shell 10 is depicted by a heavy black line.

The oil to be cooled is introduced into the interior of the shell 10, and while therein is brought into heat exchanging relation to a cooling means. In order that the oil to be cooled will be effectively distributed throughout the entire volume of the shell, partition walls or baffles 12 to 18, inclusive, (see Figs. 3 and 4) are extended in planes running longitudinally within the shell 10 so as to divide the interior space of the shell into a plurality of spaces or passages 19 to 26, inclusive, these spaces being elongated in a direction corresponding to the axis of the shell 10 and being interconnected in a manner which will be hereinafter described, so that an effective circulation of oil throughout all of these spaces may be obtained. Some of the partition walls or baffles, for example, the baffles 12 and 13, are of hollow construction for the purpose to be later explained. Cooling means are extended in the oil spaces 19—26 so as to make heat absorbing contact with the oil therein. Such cooling means preferably consist of metal tubes open at the ends so that a cooling medium, such as air, may readily pass therethrough. For this purpose I preferably employ tubes 27 as best shown in Fig. 8. These tubes 27 are nearly as long as the shell 10. The intermediate portions thereof are circular in cross-section and the end portions 28 are expanded and are formed so as to be hexagonal in cross-section. These tubes 27 are placed in side-by-side relation so that the faces of the hexagonal ends 28 will be in cooperative engagement as shown at 29 in Fig. 3 to 75

close the ends of the spaces 19—26, these hexagonal ends 28 being joined to each other and to other metal chambers of the assembly by use of solder, in accordance with the general practice of making cellular structures of radiator type.

The shell 10 has near its right end as viewed in Figs. 1 and 2, and in the upper wall thereof as also shown in Figs. 4, 5 and 6, an oil inlet port 30, an oil outlet port 31, a bypass inlet opening 32 and a bypass outlet opening 33, the openings 32 and 33 comprising longitudinally extending slots disposed substantially equidistant on opposite sides of the vertical medial plane A—A of the oil cooler. In the bottom wall of the shell 10, as shown in Fig. 5, there are secondary bypass openings 34 and 35 comprising narrow slots lying substantially in the vertical planes defined by the bypass openings 32 and 33. The partition wall or baffle 14 is shown on the medial plane A—A, Fig. 4, comprising a sheet of metal, preferably copper or an alloy thereof, having at least the front and rear edges thereof bent in angular relation for cooperative engagement with the adjacent tube ends 28. In the preferred practice of the invention however, the wall 14 is bent along lines extending longitudinally thereof and in parallel relation, thereby forming adjacent sections 36 and 37 lying at angles of 120°, to correspond to the angularity of the external faces of the hexagonal end portions 28. The horizontal partition walls or baffles 15, 16, 17, and 18, comprise metal sheets bent so as to provide horizontal sections or strips 38 connected by sloping sections or strips 39, Fig. 4, for cooperative engagement with the hexagonal tube ends 28 as shown in Fig. 3. The hollow baffles 12 and 13 are comprised of pairs of vertically disposed plates of the type described relative to the central partition wall 14. Accordingly, I have shown the hollow baffle 12 as comprising parallel metal walls 14a, and the hollow baffle 13 as comprising spaced metal walls 14b, these walls 14a and 14b differing from the partition wall 14 in vertical dimension and in the provision of circulation openings between adjacent passages within the cooler. The walls 14, 14a, and 14b have flanges 40 along the upper and lower edges thereof for soldered connection with the shell 10, and the edges of the partition walls 15, 16, 17, and 18 have flanged portions along the edges thereof for connection to the parts engaged thereby. As shown in Figs. 3, 5, 7, and 9, front and rear ends of the spaces 12' and 13', within the hollow baffles 12 and 13 are closed by vertically extending metal strips 41 and 41' of zigzag form to correspond to the profile of the surfaces of the plates 14a and 14b respectively engaged thereby, these end strips 41 and 41' being soldered in place. The upper and lower extremities of the internal spaces 12' and 13' of the hollow baffles 12 and 13 communicate with the upper and lower bypass openings 32, 33, 34, and 35, as shown in Figs. 4 and 5. The lower portions of the spaces 12' and 13' are interconnected so that these spaces will be joined in a circulation passage for bypass fluid. A feature of the invention is to provide means external of the shell 10 to connect the lower extremities of the spaces 12' and 13'. As best shown in Figs. 2, 4, and 5, I apply to the exterior face of the bottom wall of the shell 10 an arcuate pan 42 which cooperates with the shell 10 to form an arcuate passage 43 connecting the bypass openings 34 and 35 of the shell. This pan 42 has a bottom wall 44 with peripheral walls or lips 45 extending upward into engagement with the shell

10. Under certain conditions of operation, as will be hereinafter explained, a bypass flow of oil will enter the inlet opening 32 as indicated by the arrow 46 of Fig. 5, will pass downward through the interior space 12' of the hollow baffle 12. This oil will then flow across the interconnecting channel 43 and, entering the port 35 as indicated by arrow 47, will pass upward through the interior space 13' of the hollow partition wall 13, and thence out through the outlet bypass opening 33.

On the top of the shell 10 I provide an oil inlet space 48 which connects the inlet port 30 and the inlet opening 32 both with an inlet fitting 49 to which oil piping from a pump associated with the engine may be connected as indicated at 50. Also, on the top of the shell I provide an oil outlet space 51 providing connection with the outlet port 31, this oil outlet space being formed in part by an oil outlet port fitting 52, a partition wall 53 having the form shown in dotted lines in Fig. 1, and an outer arcuate wall 54 which extends also over the oil inlet space 48. As shown in Fig. 10, the outlet port fitting 52 has a circular top wall 55 with an opening or port 56 therein. From the periphery of the wall 55 a cylindrical wall 57 extends downward, the rightward portion of the wall 57 having a semi-cylindrical skirt 58 extending downward as best shown in Figs. 4 and 10 to make engagement with the upper wall of the shell 10, to serve as a partition wall between the oil outlet space 51 and a bypass outlet chamber 59 which communicates with the bypass outlet opening 33. Adjacent the oil inlet fitting 49, there is a port fitting 52a which is similar in form to the fitting 52 shown in Fig. 10, but is rotated on its axis through an angle of 180° so that, as shown in Fig. 6, the semi-circular skirt 58a thereof will lie below the leftward portion of the fitting and an opening 61 will exist under the rightward portion of the cylindrical wall 57a to connect the interior of the fitting 52a with the bypass outlet chamber 59, formed in part by an arcuate wall 62 lying parallel to a portion of the shell 10 and an edge wall 63 which connects an edge of the wall 62 with the shell 10. The members 42, 54, and 62 are of the same axial length, and on the exterior of the shell 10 between the edges of the members 42, 54, and 62 arcuate strips 64 and 65 are secured in the position of radially extending flanges, to reinforce the shell 10.

To the port fittings 52 and 52a, as best shown in Fig. 2, an outlet fitting 66 is secured, this fitting 66 having an oil outlet port 67 and a bypass outlet port 68, respectively connected to the chambers 51 and 59. The bypass outlet port 68 has in association therewith a control valve 69 with means 70 for moving it between opened and closed relation to the port 68. This means 70 is shown as a thermostatic element secured in downwardly projecting relation to a threaded plug 71 which is secured in the fitting 66 above the port 68. The thermostatic element 70 is so formed that as the temperature thereof increases the valve member 69 is moved downward toward the port 68 so as to restrict or prevent flow through this port 68. The fitting 66 has an outlet 72 to which oil return piping 73 may be connected, and within the fitting 66 there is a baffle 74 for directing oil from the port 67 into engagement with the thermostat element 70.

In Figs. 2 and 4, it will be noted that the inlet port 30 for oil to be cooled is at the right or forward end of the shell and leads into the forward

end of the passage 19. In the wall 15 between the passages 19 and 20, there is an opening 75 connecting the left or rear end of the passages 19 and 20. In the front portion of the hollow baffle 12, Fig. 4, there is an opening 76 connecting the front ends of the spaces 20 and 21. The rear ends of spaces 21 and 22 are connected by an opening 77 in the lower part of the central partition wall 14, as shown in Fig. 5. The front ends of the spaces or passages 22 and 23 are connected by an opening 78, Figs. 4 and 7, which passes through the lower portion of the hollow baffle 13. The rear end of passage 23 is connected to the rear end of passage 24 by an opening 79 through the rear end portion of the horizontal wall 18. In the upper, forward portion of the hollow baffle 13 there is an opening 80 which connects the front end of the passage 24 with the front end of the passage 25. The rear end of passage 25 connects through an opening 81 in the upper part of the central wall 14 with the rear end of passage 26, and therefrom the oil will flow forwardly in the passage 26 to the outlet port 31 and thence through the oil outlet port 67 of the fitting 66. The openings 76, 78 and 80 respectively through the lower front portions of the hollow baffles 12 and 13 are formed in the manner shown in Fig. 7 wherein openings 78 and 80 are shown. Referring in particular to the opening 78, the plates 14b are cut as shown in Fig. 9 to outline the opening 78 and vertical and horizontal portal members 82 and 83 are soldered between the edges of the plates 14b which form the opening. The horizontal or upper portal member 83 is of such length that it will extend from the upper end of the member 82 to the zigzag strip 41' which closes the front end of the space 13' within the hollow baffle 13. The opening 76 is formed from similar portal members 82a and 83a as indicated in Fig. 4. The opening 80 is outlined by portal members 82b and 83b placed in inverted relation to the members 82 and 83 in Fig. 7.

The direction of flow of oil through the oil cooler is best illustrated in Fig. 12 wherein arrows are employed to show the direction of flow from one passage to the other. It will be noted from this view that the hollow baffles cooperate with the other baffles in order to divide the space in the shell into a series of interconnected passages. These interconnected passages are joined together through openings formed in the hollow baffles and in the other baffles, as is clearly shown in the various views, particularly Fig. 12. By reason of the arrangement of the hollow baffles it will be seen that the oil to be cooled will flow along one side of a hollow baffle. It will flow through the opening in the hollow baffle and may then flow along the other side of the hollow baffle. When the device has become clogged and hot oil is delivered through the thaw-out means, it will be seen that every chamber within the oil cooler has at least one wall through which it may derive heat from a thaw-out passage. It will further be seen that the oil passes along one side of the baffle and then along the other side of the baffle, thus obtaining a maximum heat transferring efficiency and thus not only accomplishing a thawing out of the oil cooler, but insuring a substantial velocity flow through the oil cooler, and thus assuring a more rapid return to normal operation.

As shown in Figs. 2 and 11 my invention provides a simple means for simultaneously draining the oil from the oil cooling spaces and the

bypass spaces of the oil cooler. The central portion of the pan 42 is deformed so as to provide a flat wall portion 84 to which a flange 85 may be secured, this flange 85 having a threaded opening 86 communicating with an opening 87 in the wall portion 84. From an opening 88 in the bottom wall of the shell 10 a discharge tube 89 is extended down into the opening 86, preferably coaxial therewith. A plug 90 is provided to simultaneously close the opening 87 and likewise obstruct or close the lower end of the discharge tube 89 which leads downward from the bottom wall of the shell 10. This plug has a recess 91 in the inner face thereof which receives the lower portion of the discharge tube 89. The oil cooling spaces 19 to 26, inclusive, are interconnected in such manner that they will all drain down through the passages 21 and 22 when the plug 90 is removed, and at the same time oil in the interior spaces of the hollow baffles 12 and 13 will drain out through the interconnecting space 43 and the opening 87 formed by the pan 42.

The operation of the cooler is indicated from the following description. It will be perceived that the oil inlet fitting is at all times connected through the chamber 48 with the port 30 and with the bypass inlet opening 32. Also, the outlet port 31 is at all times in open communication with the outlet fitting 66. Whether oil may flow through the bypass passages 12, 43, and 13' will depend entirely upon the position of the valve member 69. Where the control means for the valve 69 comprises a thermostat, the valve will be in open position, as shown in Fig. 2, when the engine has been stopped for a long enough period of time to permit the oil in the oil circulating system to cool. Accordingly, when the engine is started after a period of inoperation, the cold oil pumped from the crank case of the engine may pass through the bypass passages of the oil cooler. At this time there may be a small or sluggish flow of oil through the oil cooling spaces of the cooler as the result in the differential in pressure between the inlet and outlet ports 30 and 31. As the oil from the engine starts to warm up, heat will be transmitted through the walls 14a and 14b of the bypass passages to warm the oil in the adjacent oil cooling spaces of the device, and as the increase in the oil temperature continues there will be a further transfer of heat into the oil in the oil cooling spaces of the device and also a gradual closing of the valve 69 due to the rise in temperature to which the thermostat element 70 is subjected, until a condition is finally reached wherein the valve member 69 substantially closes the port 68, thereby closing the outlet end of the oil bypass so that substantially the entire flow of oil from the engine will pass through the oil cooling spaces.

I claim as my invention:

1. In an oil cooler of the character described, the combination of: a shell having tubes extending therethrough, thus providing a space around said tubes through which liquid to be cooled may be circulated, said shell having an inlet port and an outlet port connected to said space; baffles in said shell dividing said space into a plurality of passages connected in series, the first of which is connected to said inlet port and the last of which is connected to said outlet port, at least one of said baffles being a hollow baffle and including a pair of spaced walls which form a thaw-out passage, one end of which is connected to said inlet port and the other end of which is connected to said outlet port, said hollow baffle

being so arranged that one passage is on one side thereof and another passage is on the other side thereof, there being a connecting opening through said hollow baffle so that the liquid to be cooled may flow first along one side of said hollow baffle and then along the other side of said hollow baffle; and means for controlling the flow of liquid through said thaw-out passage.

2. In an oil cooler of the character described, the combination of: a shell having tubes extending therethrough, thus providing a space around said tubes through which liquid to be cooled may be circulated, said shell having an inlet port and an outlet port connected to said space; baffles in said shell dividing said space into a plurality of passages connected in series, the first of which is connected to said inlet port and the last of which is connected to said outlet port, at least two of said baffles being hollow baffles and including each a pair of spaced walls which form a thaw-out passage, said hollow baffles extending longitudinally through said shell in substantially parallel relation and being connected in series, one end of one of the thaw-out passages of one of said hollow baffles being connected to said inlet port and one end of the thaw-out passage of the other of said hollow baffles being connected to said outlet port, each of said hollow baffles being so arranged that one passage is on one side thereof and another passage is on the other side thereof, there being a connecting opening through each of said hollow baffles so that the liquid to be cooled may flow first along one side of one of said hollow baffles and then along the other side of the other of said hollow baffles; and means for controlling the flow of liquid through said thaw-out passage.

3. In an oil cooler of the character described, the combination of: a shell having tubes extending therethrough, thus providing a space around said tubes through which liquid to be cooled may be circulated, said shell having an inlet port and an outlet port connected to said space; baffles in said shell dividing said space into a plurality of passages connected in series, the first of which is connected to said inlet port and the last of which is connected to said outlet port, at least two of said baffles constituting hollow baffles, each of which includes a pair of spaced walls which form a thaw-out passage, one end of one of said hollow baffles being connected to said inlet port and the adjacent end of the other of said hollow baffles being connected to said outlet port; wall means applied externally to one side of said shell and providing an interconnecting thaw-out passage connected to adjacent ends of said hollow baffles in a manner to connect the thaw-out passages thereof in series; and means for controlling the flow of liquid through said thaw-out passages.

4. In an oil cooler of the character described, the combination of: a shell having tubes extending therethrough, thus providing a space around said tubes through which liquid to be cooled may be circulated; inlet and outlet means at one side of said shell for conducting liquid through the space within said shell; a pair of hollow baffles extending in spaced relation through the interior of said shell from said side thereof where said inlet and outlet means are located to the opposite side thereof, said hollow baffles dividing said space in said shell into a plurality of series connected passages, the outer faces of said hollow baffles being exposed to at least a part of said passages; wall means at said other side of said shell for

connecting the interiors of said hollow baffles together, thus connecting them in series; and means at said first side of said shell for placing both the inlet and outlet means in open communication with the interiors of said hollow baffles so that liquid may pass directly therethrough in heat exchanging relation to said passages and in multiple flow relation with the flow through said passages.

5. In an oil cooler of the character described, the combination of: a shell having heat exchange means therein and having inlet and outlet passage means communicating with the interior of the shell; wall means within said shell for defining oil passages whereby the oil to be cooled will be carried back and forth in said shell in heat exchanging relation to said heat exchange means from said inlet passage means to said outlet passage means, said wall means comprising at least one hollow baffle having inlet and outlet ports connecting its interior with said inlet and outlet passage means and thereby providing a thaw-out passage within said shell, said hollow baffle being so positioned relative to the path of flow of oil in said shell that oil to be cooled will flow first across one side of said hollow baffle and then across the other side of said hollow baffle; and means for controlling a flow of liquid from said inlet passage means through said thaw-out passage to said outlet passage means.

6. In an oil cooler of the character described, the combination of: a shell having heat exchange means therein and having inlet and outlet passage means communicating with the interior of the shell; wall means within said shell for defining oil passages whereby the oil to be cooled will be carried back and forth in said shell in heat exchanging relation to said heat exchange means from said inlet passage means to said outlet passage means, said wall means comprising a plurality of hollow baffles placed within said shell so that a side face of one of said hollow baffles will be adjacent to and spaced from the side face of another of said hollow baffles, the interiors of which are connected to said inlet and outlet passage means so as to form thaw-out passages, said hollow baffles being so positioned in said shell that oil to be cooled will flow within

said shell first across one side and then across the other side of each of said hollow baffles; and means for controlling a flow of oil through said thaw-out passages from said inlet passage means to said outlet passage means.

7. In an oil cooler having a shell, heat transfer means in the shell, an oil inlet port and an oil outlet port communicating with the interior of said shell; spaced walls forming a hollow baffle disposed in said shell to define passage means for a flow of oil within said shell from said inlet port to said outlet port, the interior space of said hollow baffle being isolated from the flow of oil in said passage means defined within said shell, the interior space of said hollow baffle comprising a thaw-out passage and said hollow baffle being positioned so that both sides thereof will be exposed to oil within said shell, and said hollow baffle having a transverse port extending from one side to the other thereof and through both of said spaced walls for transfer of the oil to be cooled from one part to another of said passage means; and means for directing a flow of thaw-out fluid through said thaw-out passage of said hollow baffle, said thaw-out fluid being other than the oil flowing through said passage means.

8. In an oil cooler of the class described, the combination of: a shell having inlet and outlet means communicating with the interior thereof and having a heat absorbing means therein; baffle means within said shell for guiding the oil to be cooled from said inlet to said outlet means, at least one of said baffle means comprising a hollow wall projecting from one bounding wall of said shell into the interior space of said shell and toward another bounding wall of said shell, said hollow wall being so formed that it provides a passage within said shell in transverse relation to said hollow wall through which the oil to be cooled may flow from the interior space of said shell adjacent one face of said hollow wall to the space within said shell adjacent the opposite face of said hollow wall; and means for passing a controlled flow of warm-up fluid through the interior space of said hollow wall, said warm-up fluid being other than the oil which flows through said passage.

WALTER R. RAMSAUR.
